CLAIM

The ornamental design for a bicycle seat bottle opener, as shown and described.

DESCRIPTION

FIG. 1 is a right side view of the bicycle seat bottle opener; FIG. 2 is a front view of the bicycle seat bottle opener; FIG. 3 is a top view of the bicycle seat bottle opener, with a split ring inserted therein; FIG. 4 is a perspective view of the bicycle seat bottle opener; FIG. 5 is a bottom view of the bicycle seat bottle opener; and, FIG. 6 is a bottom perspective view of the bicycle seat bottle opener, illustrating a bottle opener portion under the bicycle seat.

The broken lines included in the drawings herein are shown for illustrative purposes only and forms no part of the claimed design. However, the broken lines are illustrative of approximate scale relative to a bottle opener portion used to engage a bottle cap for removal.

The present bottle opener is characterized by being in the shape of the seat of a bicycle, as shown and described.
